DESIGN FOR A CASE FOR TOILET ARTICLES

Abraham L. Siegel, Brooklyn, N. Y., and Hiram A. Jacobs, Minneapolis, Minn., assignors to A. L. Siegel Co., Inc., New York, N. Y., a corporation of New York

Application September 9, 1933. Serial No. 49,227

Term of patent 7 years

To whom it may concern:

Be it known that we, ABRAHAM L. SIEGEL and HIRAM A. JACOBS, citizens of the United States, residing at Brooklyn and Minneapolis, in the counties of Kings and Hennepin and States of New York and Minnesota respectively, have invented a new, original, and ornamental Design for a Case for Toilet Articles, of which the following is a specification, reference being had to the accompanying drawing, forming part thereof, in which:

Figure 1 is a perspective view showing one side

of the closed case for toilet articles, showing our new design;

Figure 2 is a plan view of the reverse side of the closed case depicted in Figure 1, and

Figure 3 is a perspective view of the case in an open position.

We claim:

The ornamental design for a case for toilet articles as shown and described.

In testimony whereof we affix our signatures.

ABRAHAM L. SIEGEL.
HIRAM A. JACOBS.
